BUFFER MECHANISM**Karl W. Maier, Cheshire, Conn., assignor to Olin Mathieson Chemical Corporation, a corporation of Virginia****Application April 12, 1957, Serial No. 652,506****5 Claims. (Cl. 123—7)**

This invention relates to buffer mechanisms and deals in particular with such mechanisms adapted to soften or cushion impacts of bodies moving at ultra high velocities, such as pistons of powder-actuated or air-operated tools.

The device is effective to accomplish cushioning within a relatively short interval of linear distance measured from the point of initial impact to the point at which the body is ultimately brought to rest. The term "ultra high frequency" defines velocities of the order of 100 to 200 feet per second while the term "short linear distance" characterizes distances as short as $3\frac{1}{1000}$ to $4\frac{1}{1000}$ of an inch.

One of the perennial problems encountered in the art of driving or shooting projectiles, such as nails, bolts, studs, drill bits and other slugs or fasteners into a work piece, utilizing a piston propelled by compressed air or hot gases has been the selection and control of powder charges or air pressure, as the case may be, effective to drive the projectile into the work piece without damaging the tool or overdriving the fastener.

It is well known that the resistance offered to a given design of slug or fastener varies over wide ranges from work piece to work piece; the resistance varies, in fact, from area to area in a given work piece. For example, a projectile driven into concrete meets a resistance different from the value of resistance encountered in wood or a cinder block. Correspondingly, resistance to a projectile may vary from area to area within a given slab of concrete.

As a result of the wide range of resistances encountered, frequently the piston utilized to drive a fastener arrives at the end of its stroke with a very considerable portion of its energy unconsumed.

Frequently this unconsumed energy is dissipated by overdriving the fastener or by failure of the piston, both occurrences being highly undesirable.

Usually a stud is driven into a work piece to a certain predetermined depth with an allowed maximum or minimum depth defining a tolerance. By the term "overdrive" is meant driving a stud or other projectile beyond the tolerable distance.

It is apparent that impacts occurring at velocities of 100 to 200 feet per second originate violent shock waves; the impact force being proportional to the impact velocity. In order to reduce impact forces, it is highly desirable to reduce the relative impact velocity of the impacting surfaces. In the present invention a reduction of impact force is accomplished by bringing the impacting surfaces of the piston and the cylinder together along a pair of mating tapered contours, after the fastener is set, in a manner which will be become more apparent hereinafter.

In this fashion the full longitudinal velocity of the driving piston is utilized to drive the fastener but the piston collides with a cushioning device with a reduced impact force. This is so because the value of the relative impact velocity of the impacting surfaces of the piston and the cylinder, in the area of the taper, is much

2

less than the longitudinal velocity and is proportional to the angle of taper.

In addition to variations in resistance occurring in different materials or in different area of a given material, 5 the problem of over-driving a slug beyond tolerable limits stems from the fact that it is frequently necessary to have an exceedingly high powered stroke, initially, to start a fastener into the work and thereafter much less power is necessary to keep the projectile moving into the work. 10 The buffer device of the present invention is effective to cushion exceedingly fast moving pistons within a relatively short distance and is thereby effective to regulate accurately the depth to which a fastener is driven.

Accordingly, it is a particular object of the present invention to provide a novel buffer mechanism.

It is a further object of the invention to provide a buffer mechanism for powder-actuated or air-operated tools, or the like, effective to cushion the piston within a short interval of time and within tolerable overdrive 20 limits.

Another object of the invention is the provision of a piston-cylinder arrangement in the above general class of devices where one end of the cylinder wall is provided with a plurality of radially disposed slots to define a 25 plurality of tines or prongs and reinforcing the exterior of the cylinder in the vicinity of the tines with a winding or serving of ends of Fiberglas filament or yarn suitably bonded with plastic to define a collet.

A further object of the present invention is the provision 30 of a structure having the longitudinal strength or compressive resistance of a tube or cylinder while having radial resilience for buffering.

A buffer mechanism embodying certain features of the present invention may comprise a tubular barrel member, 35 a piston having a tapered contour disposed in the barrel and adapted to be driven along the longitudinal axis of the barrel in response to gas pressure, the forward end of the cylinder being formed with an internal tapered contour adapted to complement the tapered piston, the forward end of the cylinder wall being formed with a plurality of radially disposed grooves or slots for dividing the wall into a plurality of tines, the interior tapered portion and the tines being so disposed that when the piston is advanced to bring the mating tapered portions 40 into contact whereby the piston tends to spread the tines and a band of glass reinforced plastic disposed around the exterior of the tines effective to retain the tines against splitting.

Other features and advantages of the present invention 50 will become apparent from the succeeding specification and drawings wherein:

Fig. 1 is a longitudinal sectional view of a buffer mechanism embracing the principles of the present invention. The section is defined by a plane passing through 55 the longitudinal axis of the mechanism and cutting a pair of opposed tines.

Fig. 2 is an end view of the left end of the device shown in Fig. 1.

It is to be distinctly understood that although the exemplary embodiment of the invention shown and described herein illustrates the principles of the present invention as adapted to a powder actuated tool (wherein a powder charge is burned to advance a piston which, in turn, drives a projectile such as a nail or stud), it is 60 entirely within the spirit and scope of the invention to apply the principles thereof, namely, the scheme for buffering, to any piston tool no matter what its source of motivation or the character of the element upon which the piston performs work.

70 Referring now to the several figures there is shown in the illustrated embodiment of the invention a cylinder or barrel 10 having a bored plug 11 in threaded engagement

therewith for receiving a conventional cartridge 12. Disposed within the barrel and immediately ahead of the plug is a piston 13 having a base 14, a tapered neck 16 and a head 17. A compression chamber designated by the reference numeral 15 is bounded by the plug 11 and the base of the piston. The piston is provided with a suitable gas seal at the base and in the form of piston rings 18 and is adapted to move along the interior of the barrel in the direction shown by the arrow until the tapered neck 16 encounters a mating tapered portion 19 formed on the interior of the barrel.

In customary manner, a suitable projectile, such as the stud 21 disposed in the bore of the barrel is driven into a work piece when the head 17 strikes the stud.

The forward portion of the barrel or the left end, as viewed in Fig. 1, is formed with a plurality of slots 22 so as to divide the barrel into a plurality of prongs or tines 23. For convenience, this portion of the barrel may be referred to hereinafter as a chuck or collet.

The chuck end of the barrel is undercut to receive a winding or serving of strands or filaments of Fiberglas wrapped about the undercut portion and suitably impregnated with a plastic binder so as to form a composite band there around as indicated generally by the reference numeral 24. It is important that the strands or filaments of Fiberglas wound or served around the exterior of the collet be so arranged that a bursting load tending to swell the tines or prongs outwardly will place the Fiberglas under a hoop stress or a tensile stress. By so disposing the ends of Fiberglas, it is possible to take advantage of the maximum tensile strength available in Fiberglas reinforced plastics which, as is well known, is in excess of 200,000 lbs. per square inch.

Frequently it may be desirable to provide a loose shim or liner of relatively light gauge metal between the band of Fiberglas reinforced plastic and the exterior of the tines, as at 20, to avoid undue friction or wear between the interfaces of the tines and the band.

The operation of the tool is as follows:

Assume that a projectile such as the projectile 21 has been disposed within the barrel 10 and that the piston 13 is retracted to the position shown in Fig. 1.

Firing of the cartridge 12 by well known means will generate hot gases in the chamber 15 which rapidly expand to drive the piston to the left, as viewed in Fig. 1, whereupon the head 17 engages and moves the stud 21 out of the barrel and drives it into a workpiece.

In tools of this nature, it is desirable, as stated previously, to decelerate or stop the piston as soon as possible after it has driven its projectile and within the very short additional length of stroke allowed for overdrive.

Accordingly, the tapered neck 16 and the mating tapered portion 19 of the barrel are so disposed that upon a given length of stroke of the piston the corresponding tapered portions engage one another to load the collet tending to move the tines outwardly in turn loading the band 24.

Since the structural element of the band 24 is Fiberglas having a very high tensile strength and a considerable elongation (more than 2%) a high energy is readily absorbed by the band in swelling without exceeding the elastic limits of the Fiberglas.

It is frequently desirable to form the tapered portion 19 on the barrel such that the included angle, alpha, represented by the dotted lines is slightly greater than the corresponding angle, beta, formed on the neck of the piston. In this way there is a gradual loading of the reinforcing band 24 wherein the mating tapered portions first make line contact with one another and thereafter fit snugly.

Inherently, the tapered formation or contour of the piston and the cylinder have the following advantages:

(a) Concentration of stresses on the piston are avoided.

- (b) There is a transfer of longitudinal motion of the piston into radial motion of the tines and into hoop stress in the Fiberglas.
- (c) There is a reduction in velocity of impact between the impacting surfaces of the piston and cylinder and a corresponding reduction of surface stress.
- (d) The surface of impact is increased.
- (e) There is a maintenance of longitudinal stiffness of the barrel while using radial resilience of the tines for buffering.
- (f) Self-releasing tapers (tapers whose included angles are large enough to avoid frictional seizing upon impact) may be selected effective to reduce the velocity of impacting surfaces of piston and cylinder from 200 feet per second to as low as 50 feet per second.

It is anticipated that various arrangements and modifications of the present invention may be devised wherein: (1) a wide variety of plastic binders may be utilized to reduce the winding of Fiberglas to a composite mass (2) the density of the Fiberglas within the composite mass may be varied by varying, for example, the tension with which the glass filaments are wound (3) the design of the mating tapered portions may be adjusted to include different tapers or contours. Nevertheless all these modifications are entirely within the spirit and scope of the present invention.

What is claimed is:

- 1. A buffer mechanism for cushioning the impact of a piston colliding at an ultra high velocity comprising a tubular member for slidably receiving the piston, means for applying fluid pressure to the piston to drive the piston, one end of said tubular member being formed with a plurality of tines, the internal surface of said tubular member being formed in the vicinity of said tines with a tapered contour adapted to mate with a corresponding tapered contour formed on the piston, said piston being effective to spread the tines when the piston is driven in a direction which tends to bring the tapered portions into engagement, and a winding of glass reinforced plastic disposed about the exterior of the tines effective to resist the tendency for the tines to spread.

- 2. A buffer mechanism for cushioning the impact of a piston colliding at an ultra high velocity comprising an apertured member for slidably receiving the piston, a compression chamber within the member for applying fluid pressure to the base of the piston to drive the piston, one end of said member being formed with a plurality of tines, the internal surface of the piston being formed with a tapered contour adapted to mate with a corresponding tapered contour formed on the piston and effective to spread the tines when the piston is driven in a direction which tends to bring the tapered portions into engagement and a band of glass reinforced plastic disposed about the exterior of the tines effective to resist the tendency for the tines to spread whereby the piston is brought to a cushioned stop.

- 3. A buffer mechanism for cushioning the impact of a piston colliding at ultra high velocity comprising a tubular member for slidably receiving the piston, a compression chamber within the tubular member for applying fluid pressure to the head of the piston, one end of said tubular member being formed with a plurality of tines, the internal contour of the tubular member being formed with a tapered portion adapted to mate with a corresponding tapered portion formed on the piston and effective to spread the tines when the piston is driven in a direction which tends to bring the tapered portions into engagement, a band of glass reinforced plastic disposed about the exterior of the tines effective to resist the tendency for the tines to spread whereby the piston is brought to a cushioned stop and a shim disposed between the interfaces of the tines and the glass reinforced band to protect the inner diameter of the band.
- 4. A buffer mechanism adapted to cushion the impact

between a piston moving at an ultra high velocity upon collision with a piston cylinder wall comprising a cylinder having a compression chamber at one end thereof and a tapering internal contour at the other end thereof, the walls of said cylinder being formed with a plurality of radially disposed slots in the vicinity of said tapered portion and a composite band of glass reinforced plastic disposed about said cylinder in the area of said slots effective to retain the slotted end of the cylinder against a bursting load.

5. A buffer mechanism adapted to cushion the impact between a piston moving at an ultra high velocity upon

collision with a piston cylinder wall comprising a cylinder having a compression chamber at one end thereof and an internal tapered portion generally defining a frustum of a cone in cross section at the other end thereof, the walls of said cylinder being formed with a plurality of radially disposed slots in the vicinity of said tapered portion and a composite band of glass reinforced plastic disposed about said cylinder in the area of said slots effective to retain the forward end of the cylinder against bursting, said glass taking the form of a circumferential winding of filaments.
